DEVICE FOR MAKING TUFTED ARTICLES

Mauricio Sallé, Mexico City, Mexico

Application February 8, 1951, Serial No. 209,977

16 Claims. (Cl. 112—79)

1

The present invention relates to a machine for manufacturing rugs, tapestry and the like, and which both forms and cuts loops of yarn or thread.

Various types of hand- and motor-driven devices have been produced in the past for forming a series of loops of yarn or thread in a backing material, the devices operating from the reverse side of the backing material and forming loops on the front side thereof which simulate woven carpeting or the like. A few such devices have been proposed which will not only form the loops but cut them as well, thus producing a velvet-like appearance and texture on the front of the backing material. These cutting devices have been complex and fragile and have consequently been subject to frequent breakdown. Moreover, while they have been useable to some extent for the forming and cutting of loops of thin threads of material, they have proved totally ineffective in the past, insofar as any practical production use thereof is concerned, when employed with heavy yarn of the type incorporated into floor covering.

The present invention has for its prime object the provision of a sturdy, positively acting, simple and dependable device which will both form and cut loops even of heavy yarn, and do so in a manner which will permit of a high rate of productivity.

One of the primary drawbacks inherent in prior art devices has been the fact that when the cutting action occurs a strain is placed on the thread loops. It has been thought that if that strain is applied in the direction of the length of the loop the loop will elongate and will not be cut. Consequently elaborate structure has been devised to hold the tip of the loop in a fork or the like and cut against that fork, force being applied to the loop primarily at right angles to its direction of elongation. This necessitates a complex mode of operation in such prior art devices, and further requires the use of a plurality of moving parts. Because the loops are ordinarily formed quite close to one another, all of the parts must be small, and when a number of parts must be contained within a small area the strength and dependability of those parts must necessarily suffer.

The device of the present invention operates on an entirely different principle, and as a result the number of moving parts involved are minimal—no more than in a conventional loop-forming device which does not cut the loops—and their strength is sufficiently great to provide for

2

dependable operation. The mechanism comprises in essence, a conventional loop-forming needle and a stepper blade, the latter having a sharp cutting edge. Means are also provided in the device to clamp both ends of the loop after the loop has been formed. After the ends of the loop have been clamped, the stepper blade, which has up to this point been maintained in loop-forming position, is projected further outwardly. Because both ends of the loop are clamped, the loop will be cut neatly and cleanly and without elongation. Thereafter the stepper blade (or loop-cutter) is retracted, the leading end of the thread is released, and a new loop is formed. The mechanism employed for clamping and releasing the loop ends as the loops are formed is simple, sturdy and inexpensive, and its operative action in timed relation to the movement of the needle or loop-cutter is entirely automatic.

A more specific object of the present invention is to devise such a device which is operated by an electric motor operatively connected to and driving a disk with cam grooves formed therein, that disk being centrally located in the device and controlling the movement of the various operative parts of the device in a positive manner.

To the accomplishment of the above, and to such other objects as may hereinafter appear, the present invention relates to the structure of a loop-forming and cutting device as defined in the appended claims and as described in this specification, taken together with the accompanying drawings, in which:

Fig. 1 is a side elevational view of the device of the present invention, but with the casing removed;

Fig. 2 is a face view of a disk having a cam groove and operating the loop-forming needles;

Fig. 3 is a similar view of the opposite surface of the disk showing a cam groove for operating the stepper blade or loop cutter;

Fig. 4 is a cross sectional view taken along the line 4—4 of Fig. 1;

Fig. 5 is a cross sectional view taken along the line 5—5 of Fig. 1; and

Figs. 6—10 diagrammatically illustrate the movement and position of the operative parts at various stages in the formation and cutting of the loops.

The device comprises a frame including a pair of spaced mounting plates 10 and 11 surrounded by a casing 36 and being held together by bolts

12. Motor 15 is mounted on the plate 11 by

means of bracket 16, the bracket being secured to the motor by bolts 18 and to the plate 11 by bolts 19. As here disclosed the motor is of the pistol type, having a switch 20 in the form of a trigger for convenience in operating the machine. The shaft 14 of the motor extends between the plates 10 and 11 and a pinion 13 is fast thereon.

The pinion 13 meshes with teeth on a disk 21 apertured at 24 and rotatable on shaft 25 supported between the plates 10 and 11. That face of the disk opposite the plate 10 (see Fig. 2) is provided with a cam groove 22 eccentrically located with respect to the aperture 24. The opposite face of the disk 21 (see Fig. 3) is provided with an irregularly shaped cam groove 23.

Mounted in the frame between the sides of the disk 21 and the plates 10 and 11 respectively are guide bars 27 and 28, each formed on its inner surface with a groove 29 defining a guide for the connecting rods 30 and 31, the former being provided with a roller-type follower 32 received within the cam groove 22 and the latter being provided with a roller-type follower 33 received within the cam groove 23. A block 34 is secured to the bottom of the casing 36 and the connecting rods 30 and 31 pass through and are guided by the block 34.

Attached to the lower end of the connecting rod 30 by the screws 38 is a depending arm 37, screws 40 securing a head 39 to the lower end thereof, that head carrying a pair of hollow looping needles 41. The upper surface of the head 39 is provided with a transverse groove 43, and longitudinal openings 42 extend from the top of the head 39 into the hollow needles 41, the left hand surfaces of those needles being provided with concave longitudinally extending walls 41a. The depending arm 37 is provided with apertures 49 opposite the upper ends of the longitudinal passages 42 in the head 39.

Secured to the block 34 are a pair of depending bars 57 and spaced crossbars 59 extend between the bars 57 near the lower ends thereof. Two thread-holding clamps 55, serrated at their lower ends 54, are mounted to slide vertically through the lower bar 59, the clamps being provided with stems 60 slideable through the upper crossbar 59. Springs 61 surround the stems 60, are active upon the clamps 55, and tend to urge those clamps downwardly, the extent of their downward movement being limited by engagement of the enlarged clamp heads 55a with the upper surface of the lower crossbar 59.

Secured to the lower end of the connecting bar 31, by the screws 45, is an arm 44 on which is mounted the two stepper blades 46, one positioned opposite each of the needles 41. The tips of the stepper blades 46 are notched at 47, are provided with a sharp cutting edge, and ride in the concave grooves 41a formed in the left hand surfaces of the needles 41. Fastened to the arm 46 is a U-shaped bracket 62 having upper and lower flanges 62a through which a rod 63 is vertically slideable, a spring 64 being active on the rod 63, as by means of cotter pin 64a, so as to urge the rod 63 downwardly, the rod 63 carrying at its lower end a loop-holding clamp 65 serrated at its lower edge and positioned opposite the needles 41.

An arm 51 rigidly secures a conventional presser foot 52 to the stationary frame of the device, thus positively positioning that frame vertically with respect to the backing material upon which the machine is adapted to operate.

The manner of operation of this machine is

shown in Figs. 6-10. The yarn or thread 48 is passed through the apertures 49, over the needle head 39, down through a longitudinal aperture 42 therein and inside the concave needle wall 41a. When the presser foot 52 is pressed upon the backing material, rotation of the motor shaft 14 will cause the disk 21 to rotate and this will force the needles 41 to penetrate the backing material and project downwardly therefrom. The thread 48 will be carried through the backing material by the needles 41. While the needle is in this position the stepper blades or loop cutters 46 will also be moved downwardly, sliding along the concave needle wall 41a and thus penetrating the backing material through the same aperture formed by the needle 41. The degree of projection of the stepper blade 46 beyond the backing material will be determined by the length of loop desired. While ordinarily the stepper blade 46 will not project further than the concave needle wall 41a, so that no strain will be placed on the thread 48 at this point in the operation of the device, it is entirely within the scope of the present invention for the stepper blade 46 to project downwardly beyond the aforementioned position. No cutting will take place if this occurs, the thread being substantially freely movable through the apertures 49 and 42. As the stepper blade 46 penetrates the backing material, the clamp 65 will engage the backing material directly over the point where the previously formed loop passes over the backing material, this being the trailing end of the loop being formed. Hence that trailing loop end will be securely clamped against the backing material, the clamp 65 moving upwardly with respect to the arm 44 which carries the stepper blades 46. The position of the parts as thus far described is shown in Fig. 6.

Further rotation of the disk 21 will cause the needle 41 to be retracted, the stepper blade 46, however, remaining in position and thus holding the loop and definitely fixing the loop length. This position is illustrated in Fig. 7.

Further rotation of the disk 21 will cause further retraction of the needle 41 until the clamps 55 are engaged by the needle head 39, those clamps being received within the transverse groove 43, resiliently yielding under the influence of springs 61, and further clamping the thread 48 within the groove 43, the clamped portion of the thread defining the leading end of the loop being formed. The trailing loop end is still clamped against the backing material by the clamp 65. Now, with both loop ends clamped, the stepper blade 46 becomes a loop-cutter. It is projected downwardly an additional distance (compare its position in Fig. 8 with that in Fig. 7 and notice the depression in the line labelled "knives") and, because the thread cannot be drawn from either end, the thread is cut by the sharpened notched end 47 of the stepper blade-cutter member 46. This position is shown in Fig. 8.

Further rotation of the disk 21 gives rise to retraction of the stepper blade 46 to a point above the backing material, the needle 41 being projected downwardly through the backing material at a point in advance of the previously formed loop in order to commence the formation of a new loop. This position is illustrated in Fig. 9.

Thereafter both the needle 41 and the stepper blade 46 are projected through the backing material to form a new loop, as illustrated in

Fig. 10, that figure being identical with Fig. 6.

While but a single embodiment of the present invention has been here disclosed, it will be apparent that many variations may be made in the details thereof, all within the spirit of the invention as defined in the following claims.

Having thus described the invention, what I consider as new and desire to secure by Letters Patent is:

1. A machine for making rugs and tapestry, comprising a frame, a disk mounted in the frame, cam grooves formed on opposite faces of the disk, means for operating the disk, a hollow loop-forming needle having a head, a connection between the needle head and one of the cam grooves in the disk to operate said needle, a thread clamp supported in the frame in alignment with the head to engage and hold a thread laying on said head when the cam groove raises the needle head in contact with said thread clamp, a loop cutter operatively positioned to slide against the side of said needle, a loop clamp mounted on the loop cutter, a spring associated with the loop clamp to place said clamp under spring pressure when brought into contact with a loop formed in the fabric at the time the cutting blade is actuated to sever a newly formed loop, and a connection between the loop cutter and the second-mentioned cam groove on the disk.

2. A machine for making rugs and tapestry, comprising a frame, a disk mounted in the frame, a hollow loop forming needle having a head with a transverse groove in one end, a cam groove formed in one face of the disk, a connecting bar between the cam groove and the hollow loop-forming needle to reciprocate said needle, a thread clamp supported on the frame in alignment with the transverse groove in the head, a spring associated with the thread clamp placed under compression to hold the thread in the transverse groove when the cam connection retracts the hollow loop-forming needle, a loop cutter operating adjacent the needle when forming a loop in the fabric, a loop clamp attached to the loop cutter, a spring associated with the loop clamp to place same under pressure when in contact with a previously formed loop while the needle forms a new loop, and a second cam groove and connection between same and the loop cutter to operate the latter, the cam groove being shaped to project said needle and said cutter to form a loop and cause said loop clamp to engage a previously formed loop, to retract said needle until its head engages said thread clamp, and to then further project said cutter so as to cut the thus-formed loop.

3. A machine for forming and cutting loops of thread in a backing material comprising a frame, a loop-forming needle reciprocably mounted thereon, a loop cutting member reciprocably mounted on said frame so as to reciprocate adjacent said needle and having a cutting tip projectable out beyond said backing material, first means operatively on one side of said needle for clamping and releasing the trailing end of the loop to be formed, second means operatively on the other side of said needle for clamping and releasing the leading end of the loop to be formed, and moving means operatively connected to said needle, member and first and second means and effective to operate them in the following sequence: (1) projecting said needle and said cutting member through said backing material to form a loop, and clamping the trailing end of said loop, (2) retracting said needle from said

backing material and clamping the leading end of said loop, (3) further projecting said cutting member beyond said backing material to cut said loop, both ends of said loop being clamped, and (4) retracting said cutting member from said backing material and releasing the leading end of said loop.

4. The machine of claim 3, in which said first means comprises a resiliently urged element carried by said cutting member, engaging said backing material at the point where a previously formed loop extends over said backing material, said engagement occurring during the time that said cutting member is projected according to step (1) of said sequence, and said resiliently urged element being yieldable to permit said cutting member to move to its position according to step (3) of said sequence.

5. The machine of claim 4, in which said second means comprises cooperating elements on said frame and operatively connected to said needle, said elements being brought together and clamping the thread therebetween when said needle is positioned according to step (2) of said sequence.

6. The machine of claim 4, in which second means comprises cooperating elements on said frame and operatively connected to said needle, at least one of said elements being spring-urged toward the other, said elements being brought together and clamping the thread therebetween when said needle is positioned according to step (2) of said sequence.

7. The machine of claim 3, in which said second means comprises cooperating elements on said frame and operatively connected to said needle, said elements being brought together and clamping the thread therebetween when said needle is positioned according to step (2) of said sequence.

8. The machine of claim 3, in which said second means comprises cooperating elements on said frame and operatively connected to said needle, at least one of said elements being spring-urged toward the other, said elements being brought together and clamping the thread therebetween when said needle is positioned according to step (2) of said sequence.

9. A machine for forming and cutting loops of thread in a backing material comprising a frame, a loop-forming needle reciprocably mounted thereon, means operatively connected to said needle and guiding thread thereto, a loop cutting member reciprocably mounted on said frame and having a cutting tip projectable out beyond said backing material, a clamp operatively connected to said cutting member and movable therewith to engage said backing material at the point where the previously formed loop of thread extends over said backing material, thereby to clamp said thread against said backing material, said clamp being yieldably mounted with respect to said cutting member to permit the latter to project further through and beyond said backing material after said clamp has clamped said thread, means on said frame cooperable with said means for guiding thread and effective to clamp said thread between itself and said guiding means when said needle is retracted, and moving means operatively connected to said needle and said cutting member for moving them in the following sequence: (1) projecting said needle through said backing material and projecting said cutting member through said backing material to grasp the formed loop, said clamp

then clamping the previously formed loop against said backing material, (2) retracting said needle from said backing material until said means on said frame clamp said thread against said thread guiding means, (3) further projecting said cutting member beyond backing material so as to cut said loop, both ends of said loop being clamped, and then (4) retracting said cutting member from said backing material.

10. The machine of claim 3, in which said first clamping means comprises an element movable with respect to said cutting member.

11. The machine of claim 10, in which said second clamping means comprises an element movable with said needle and an element mounted on said frame with respect to which said first mentioned element is movable, said elements being brought together and clamping the thread therebetween during operation of the machine.

12. The machine of claim 3, in which said second clamping means comprises an element movable with said needle and an element mounted on said frame with respect to which said first mentioned element is movable, said elements being brought together and clamping the thread therebetween during operation of the machine.

13. A machine for forming and cutting loops of thread in a backing material comprising a frame, a loop-forming needle reciprocably mounted thereon, a loop cutting member reciprocably mounted thereon, a loop cutting member reciprocably mounted on said frame so as to reciprocate adjacent said needle and having a cutting tip projectable out beyond said backing material, first means operatively on one side of 35 said needle for clamping and releasing the trailing end of the loop to be formed, second means operatively on the other side of said needle for clamping and releasing the leading end of the loop to be formed, and moving means operatively connected to said needle, member and first

and second means and effective to operate them in the following sequence: (1) projecting said needle through said backing material to form a loop, and clamping the trailing edge of said loop, (2) clamping the leading edge of said loop, (3) projecting said cutting member through said loop to cut the same, both ends of said loop being clamped, and (4) retracting said cutting member from said backing material and releasing the leading end of said loop preparatory to forming the next loop.

14. The machine of claim 13, in which said first clamping means comprises an element movable with respect to said cutting member.

15. The machine of claim 14, in which said second clamping means comprises an element movable with said needle and an element mounted on said frame with respect to which said first mentioned element is movable, said elements being brought together and clamping the thread therebetween during operation of the machine.

16. The machine of claim 13, in which said second clamping means comprises an element movable with said needle and an element mounted on said frame with respect to which said first mentioned element is movable, said elements being brought together and clamping the thread therebetween during operation of the machine.
